[57] CLAIM

The ornamental design for a pacifier holder, as shown and described.

DESCRIPTION

FIG. 1 is a closed perspective view of a pacifier holder showing our new design;

FIG. 2 is an open, inside perspective view thereof, rotated 180°;

FIG. 3 is an open, outside perspective view thereof, showing the reverse of the design shown in FIG. 2;

FIG. 4 is a left end elevational view of FIG. 1;

FIG. 5 is a right end elevational view of FIG. 1;

FIG. 6 is a right side elevational view of the design of FIG. 2 in the open condition;

FIG. 7 is a left side elevational view thereof;

FIG. 8 is a left end elevational view in the open condition of the design of FIG. 2;

FIG. 9 is a right end elevational view thereof;

FIG. 10 is an open perspective view of another embodiment of a pacifier holder showing our new design, the open elevational view being in accordance with the first embodiment;

FIG. 11 is a left end elevational view thereof, rolled up, all other views being identical to corresponding views of the embodiment of FIG. 1;

FIG. 12 is an open perspective view of still another embodiment of a pacifier holder showing our new design, the open elevational view being in accordance with the previous embodiment; and,

FIG. 13 is a left end elevational view thereof, rolled up, all other views being identical to the embodiment of FIG. 1.

The broken line showing in the figures is for illustrative purposes only and forms no part of the claimed design.
